UNITED STATES PATENT OFFICE.

FRANK D. HOBBS AND CLARENCE HOBBS, OF LOS ANGELES, CALIFORNIA.

SCREEN LATCH.

Application filed April 9, 1927. Serial No. 182,452.

This invention relates to latches and pertains particularly to a novel construction of a catch for holding a spring tensioned window screen or shade down across the window opening in a closed position and is so constructed that it may be manipulated conveniently to be released and will automatically catch and latch the screen or shade in position when drawn down across the window opening.

The above recited and other objects of the invention will be more fully described in the following specification and exemplified in the accompanying drawings, in which:

15 Figure 1 represents a face view of a window shade or screen of the roller type showing the invention applied thereto, parts being broken away and shown in section to more fully disclose the details of construction.

20 Figure 2 is a section through the same taken on the line 2—2 of Figure 1.

25 Figure 3 is an edge view of the catch member showing a modified form of finger grip.

Figure 4 illustrates a side view of a modified form of the catch casing.

In carrying out the invention 6 represents a shade or screen which is adapted to be wound around a roller 7 which may be mounted on a window frame at its top and is designed to be rotated, to draw the curtain or screen in the direction indicated by the arrow A, by a spring mechanism, not shown.

Secured to the lower edge of the shade 6 in any desired manner is a slat 8 which is provided with a recess 9 into which is mounted a casing 10. The casing 10 is provided with top and bottom slots 11 and 12 through which projects the ends of a catch member 13 the lower end of said catch member having a hook 14 formed thereon and the upper end thereof having a finger pad or button 15 formed thereon. The catch member 13 is pivoted intermediate of its ends to the side walls of casing 10 by means of a pin or shaft 16.

Set into the top surface of a window sill 17 and secured therein, is a plate 18 which is provided with a slot 19 into which the hook portion 14 of the catch member is adapted to project and to hook under the edge 20 of said slot, the hook at all times being pressed forward by means of a flat hairpin shaped spring 21 one leg of which engages with the rear edge of the catch member below its pivoting point and the other leg there-

of engaging with the wall of the casing 10 as clearly shown in Figure 1 of the drawing. From Figure 2 it will be seen that the casing 10 is relatively narrow, so that the leaf spring 21 is maintained in an operative relation to the pivoted catch member 13 without any special means being provided to hold said spring in place. By employing this simple, detached, U-shaped leaf spring in combination with a casing of this character the assembling of the parts is facilitated and cost of manufacture lessened.

In Figure 4 the casing 10 is shown with a flange 22 at its top edge which affords a convenient manner of securing the same into position.

In Figure 3 is shown a different form of finger piece on the catch member 13 which comprises the knob 23 secured on the catch 75 to take the place of the pad 15.

By the above recited construction it will be obvious that the screen or shade 6 may be pulled down against the spring tension of the roller 7 and in so doing the inclined 80 edge 24 of the catch 13 will engage with the edge 20 of slot 19 and move rearwardly until it has passed through the slot and then will be forced forwardly by spring 21 to engage under the plate 18, thus the shade or 85 screen will be latched to the window sill 17 in a downward or closed position.

Having thus described our invention what we claim is:

The combination, with a vertically movable body, of a latch construction comprising a casing within said body, a latch member pivoted intermediate its ends in said casing and having its ends projecting through apertures therein; a hook on one of the ends 90 of said latch member; a plate beneath said vertically movable body provided with a slot arranged in the path of said hook, and a flat detached hairpin shaped spring disposed in said casing having one of its legs 100 engaging with said latch and its other leg with a wall of said casing to keep the hook yieldingly pressed forwardly in engagement with the edge of the slot in said plate, said casing being sufficiently narrow to maintain said spring in an operative position with relation to said latch member.

In testimony whereof we hereunto affix our signatures.

FRANK D. HOBBS.
CLARENCE HOBBS.
